UNITED STATES PATENT OFFICE.

LOUIS BURGER, OF CHICAGO, ILLINOIS.

DESIGN FOR A SPOON.

SPECIFICATION forming part of Design No. 22,257, dated March 7, 1893.

Application filed January 3, 1893. Serial No. 457,174. Term of patent 3½ years.

To all whom it may concern:

Be it known that I, LOUIS BURGER, a citizen of the United States, residing at Chicago, county of Cook, and State of Illinois, have invented and produced a new and original Design for Souvenir Spoons, &c., of which the following is a specification, reference being had to the accompanying drawing, which is a fair illustration thereof.

The leading feature of my invention consists in the handle, the end or head portion of which is in the form of a flat elongated plate with a rounded end, upon the face of which plate appears a picture representing part of a ship, with figures arranged as shown. Adjacent to the flat, elongated plate portion is a medallion of Columbus, the margins of which

are in scroll lines. At the rounded end of the flat, elongated plate the latter is marked with lines presenting the partial illustration of a globe. The shank portion between the medallion of Columbus and the inner end has a curved outline, with intermediate depression. The bowl has a picture representing the presentation by Columbus at court of natives of North America.

What I claim as new, and desire to secure by Letters Patent, is—

The design for a spoon, substantially as shown and described.

LOUIS BURGER.

In presence of—

J. N. HANSON,
W. N. WILLIAMS.
